UNITED STATES PATENT OFFICE

WILLIAM L. MCGINLEY, OF DALLAS, TEXAS

DETACHABLE SERVICE TRAY

Application filed August 15, 1930. Serial No. 475,502.

This invention relates to improvements in detachable service trays and has in particular an object to provide a portable tray with a suitable bracket frame which may be readily connected detachably upon some portion of an automobile, but which when removed therefrom, may be readily stacked one upon another, and still hold the several units of the stack in vertical arrangement, without necessitating removal of any part from the tray.

Heretofore, it has been thought necessary in manufacturing trays having rigidly attached support frames therefor, to provide such frame with an adjustable lever or leg having a slot or eye near one end through which a rigid bracket forming part of the frame is threaded, so that such leg may be adjusted to a position nearer or farther from the vertical surface of a supporting part, as of a vehicle door while overhanging bent ends of other portions of the supporting frame would rest directly upon the upper edge of such door or other support.

Such threaded construction however, has many objectionable features among the rest being the uncertain and weakened effect of such slot or eye upon said leg or brace resulting in a twisting movement of the leg or brace upon the bracket. The former manner of attempting correction of this weakness in the supporting frame for the tray, resulted in an objectionable widening of the brace about the eye which is otherwise quite unnecessary for the strengthening effect which is needed, and resulting in undesired weighting of the brace itself.

It is an object of my invention to strengthen the desirable adjustable connection between the brace and the bar or bracket which is attached to the bottom of the tray but spaced therefrom, and without forming the objectionable eye or slot in the brace itself. It is also further desired that my service tray with attached frame shall be strong in construction and easily folded into small space when not in operative position upon the vertical wall to receive it, and I especially desire that the arrangement for mounting the brace upon the bracket shall provide strong and

novel means for resisting lateral or twisting strains to which this leg or brace must be subjected when the tray above it is to support quite heavy loads.

The present invention consists in the particular construction and arrangement of the parts by which the objects are accomplished, as described in the specification, recited in the appended claims, and as illustrated in the drawings, in which—

Figure 1 is a side elevation of my service tray shown in position upon an automobile door, the latter being shown in transverse vertical section;

Figure 2 is an inverted plan view of the tray with the brace in transverse section;

Figure 3 is a detail vertical section taken in a plane indicated by the line 3—3 of Fig. 1;

Figure 4 is a detail vertical section in a plane indicated by the line 4—4 of Fig. 2;

Figure 5 is a perspective view of the spaced element slotted to receive the brace;

Figure 6 is a side elevation of my service tray, showing a modified form of brace and latch therefor, and a portion of the tray being shown with parts broken away;

Figure 7 is a detail vertical section shown in a plane indicated by the line 7—7 of Fig. 6;

Figures 8 and 10 are detail vertical sections shown in the planes indicated by the lines 8—8 and 10—10, respectively of Fig. 6;

Figure 9 is a transverse section of the brace member shown in the plane indicated by the line 9—9 of Fig. 8;

Figure 11 is a detail view of a further modified form of brace member and parts to which it is connected, parts of the tray being shown in vertical section, and

Figure 12 is a detail vertical section shown in a plane indicated by the line 12—12 of Fig. 11.

The tray may be of any desired construction, the tray 1 being shown of general rectangular shape with rounded corners. This tray is usually made of some form of sheet metal, such as aluminum, but may be of any equivalent material. I securely attach two spaced supporting brackets 4 upon the bot-

tom of the tray, transversely thereof, and which lie flat upon the bottom of the tray, the forward end 5 of each strip being bent downwardly to form a rigid leg, and the opposite end 6 bent downwardly at 7 on each strip to form a leg, the end 6 of each being spaced from the tray slightly, as shown at 8, to accommodate a rubber sleeve 9 as a cushion device.

Parallel with the two brackets 4 and between them, a supporting bracket 10 composed of a strip of metal is attached to the tray, the forward end 11 being attached to the body of the tray and bent obliquely from the bracket to fit the flange portion of the tray, as at 12. The opposite end 13 of this bracket 10 is bent upwardly and outwardly at 14 from the main portion of the bracket, and is secured to the flat bottom of the tray as at 15.

By means of the bent portion 14 and a lengthened end portion 11, a desired space 16 results between the support 10 and the bottom of the tray 1 to permit suitable adjustment of the brace element later to be described. At this point it is to be noted that the ends 6 extend over and beyond the edge of the vertical wall upon which the tray is to be supported, while the end 13 of the supporting bracket 10 will rest in about the same vertical plane as the inner surface of said wall, which latter may be an automobile door.

The spaced supporting member 10 serves as an adjustable mounting for an inclined brace member 17 which is formed as a flat blade or strip which readily extends through an elongated slot 18 of the support 10, and is provided with transverse pins 19 and 20 which, in the bracing action of the member 17, are forced against the upper and lower surfaces of the support, respectively, as shown very clearly in Fig. 3, this construction permitting movement of the member 17 lengthwise of the bar 10, and toward and from the supporting wall of the vehicle. The lower end of the brace is provided with a flexible pad 21 of rubber or other compressible material adapted to bear against the wall. When the brace 17 is drawn away from the wall, the brace may readily be raised into the broken line position shown in Fig. 1 to permit stacking of a number of trays one upon another, or resting one of them upon the supporting legs 5 and 6.

Rivets such as shown at 22 may serve for securing means for the brackets, though they may be positioned at any suitable point on the latter. The support 10 is provided with openings 23 for such rivets. Prior constructions have ordinarily made use of a bracing member positioned in a plane transverse of the supporting member 10, while much greater strength may now be obtained by the brace 17 which is inserted in the elongated slot 18 and always lies in the plane of such slot.

The lower end 24 of the brace 17 is usually twisted into a plane at right angles to the body of the brace as shown at 25, to provide suitable support for the pad 21. When the tray is to be released from the supporting wall, the lower end 24 will be swung upward in the direction of the tray as the pins 19 and 20 serve as a hinge device for said movement, and I provide a clip 26 formed of a metallic strip which is bent into a U-shaped form, as shown at Fig. 4. This operation results in flexible arms 27 normally approaching each other and permitting the edge of the lower portion of the brace 17 to be forced into this clip so that the latter may hold one end of the brace in its upper position temporarily. The clip 26 is supported by the same rivet 27 which serves the additional purpose of securing the end 13 of the bar 10 to the bottom of the tray. The clip thus opens downwardly.

The above described arrangement of the brace 17 has a blade movable in the slot 18 and positioned in a plane transverse of the wall upon which the tray is to be supported, affords a very positive resistance to a force acting longitudinally of the support 10. This mounting of the upper end of the brace in the slot 18 also makes possible the provision of as long locking pins 19 and 20 as may be desired which by their pressure upon the bar 10, as shown in Fig. 3 results in a remarkable gripping action when the pad 21 is pressed against the supporting wall.

In Figs. 6 to 10 inclusive, I show a modification of the particular connection of the brace member 28 with the supporting spaced member which I have shown clearly in Figs. 6, 7, 8 and 10, as slightly spaced but separate track bars 29 and 30 which is so spaced that they may receive between them the member 28, thus providing the equivalent of the slot 18 of the support bar 10 of the first form. One of these bars—29 is shown clearly in Fig. 6, the other—30 being removed in this view. Both forms of supporting member however, serve the purpose well of providing a narrow and elongated aperture 31 (18 in Fig. 5), for receiving the blade-like member 28 or 17 therein, and resisting well, strains presented laterally, as well as the strain always present when the pad 32 (or 21) is pressed against the supporting wall of the vehicle.

The two bars 29 and 30 are secured to the tray by the provision of a rivet at each end, and a metal loop 33 apertured at 34 to receive a rivet, is applied over the end of the bars so that the rivet 35 passes through the said aperture, the spacing aperture 31 and the metal of the tray 1. A similar rivet 37 passes through a similar loop 36, through the aperture 31, the tray metal, and an aperture in a clip 38, as shown in Fig. 10, to hold the bars 29 and 30 to the tray bottom and to pro-

vide means for receiving the lower end 39 of the member 28 when in folded position.

The brace member 28 is, in this alternative form, strengthened by being formed from a single piece of material, usually of sheet metal in substantially rectangular shape, which is bent upon itself along a central longitudinal line, to bring the lateral edges 40 in contact, as shown in the sectional view of Fig. 9, whereby the ultimate thickness of the bar 28 is doubled to give far greater resistance to both lateral and direct strains on the member.

A further advantage in this folded type of brace member 28 arises from the opportunity that it affords for splitting the upper end thereof for a short distance, and then bending the separate ends or tips 41 apart and at right angles to the brace, to bear directly upon the upper surface of the supporting members 29 and 30. Other portions of the member 28 somewhat beneath the parts 41 are also bent outwardly from the folds of the brace member to form lateral wings 42 which normally bear upwardly against the support bars, as shown in Figs. 6 and 8. The portion of the blade 28 between the wings 41 and 42 is inserted between the bars 29 and 30 in the space 31, for movement lengthwise thereof.

The lower end 39 of the brace is formed into a flattened portion 43 by flattening out the folds, and the pad 32 is mounted upon this portion which is approximately square in outline. Both braces 17 and 28 are exceedingly strong in a direction lengthwise of the supporting members. The end 39 of the brace 28 may be readily folded upwardly into contact with the downwardly hanging clip 38.

The modified form of brace and support bar shown in Figs. 11 and 12 has the similar structure of a flat thin brace member 45 which is inserted in the slot 18 of the elongated supporting bar 54 whose end 52 is attached to the tray 1 by the rivet 53, somewhat like the securing means of Fig. 1. While the brace 45 is pivoted upon the slotted bar 54 by the provision of a transverse pin 55 in the brace resting upon the bar, upward strain of the brace member is resisted by an upper extension 46 of the latter designed to contact the lower plate or bottom of the tray 1, when the flexible pad 32 presses against the vertical supporting wall. A form of bayonet slot 47 is formed in the lower end of the brace 45 and opens outwardly and upwardly, as shown in Fig. 11, to permit receiving a closed part 56 of the bar 54.

The slot 47 is partially closed by an inwardly extending lip 51 which is integral with the main portion of the brace 45. The folds of the brace 28 separate at 44 to form the support 48, but the lower end of the brace 45 which is a solid blade, is flattened at right angles to the blade to form the support 50

for the pad. In latching the blade 45 in idle position, the lip 51 enters the aperture 57 above the connection 56 of the bar 54, and the entire blade is then moved bodily lengthwise to temporarily latch it in this horizontal position, as shown in broken lines in Fig. 11. This blade 45 is somewhat thicker than the blade 17, but is held in operative position to brace the tray by contact with the tray bottom and contact of the pin 55 with the support 75 bar 54.

In all forms shown in this application, a blade comprising an elongated blade is inserted in a long, slender slot in a supporting bar secured at its ends to the bottom of the tray, and adjustable in said slot by moving the brace member while the upper end thereof is inclined at the proper angle to the tray to loosen the grip of the brace to the support, the tray or both. The brace may thus readily be folded into inactive or idle position adjacent the tray, as shown in broken lines in Figs. 1 and 11. In all these forms, the flat blade has its edge facing the wall of the element supporting the tray, when the tray is resting on the wall. The supporting legs 5 and 6 permit stacking the trays of a pile while in parallelism, and is considered more or less conventional in the art, and is not therefore described in detail.

Having now particularly described the nature of my invention, its structure and function, what I claim and desire to secure by Letters Patent, is—

1. The combination of a receptacle having a supporting member slotted longitudinally and secured at its ends to said receptacle but spaced therefrom intermediate the ends, and a brace member formed of flat metal movably mounted in said slot with its edge facing a vertical support upon which the receptacle rests, and having gripping means at one end for engaging both the under and upper surfaces of said slotted member for holding the brace in various positions of adjustment along the slot, and means at the opposite end of the blade body for carrying a pad to contact the said vertical support.

2. The combination with a service tray adapted to be hooked over a vertical support of a slotted member upon the under side of the tray and a brace shiftable on said slotted member toward and from a vertical support upon which the tray is hooked, one end of said brace extending through the slot in said member whereby the brace may swing in said slot longitudinally thereof to a collapsed position under the tray and means on said end of the brace for holding the brace in an extended position against the side of said vertical support against which the brace is adjusted.

3. The combination with a service tray adapted to be hooked over a vertical support of a slotted member upon the under side of

the tray and a brace shiftable on said slotted member to and from engagement with the side of a support over which the tray is hooked, said brace having an end portion extending through said slot whereby the brace is adapted to be swung in said slot longitudinally thereof and means on said brace on the opposite sides of said slotted member for retaining said brace on the slotted member and adapted to contact the opposite sides of said slotted member when the brace is against the side of said vertical support to hold the brace extended.

In testimony whereof I hereunto affix my
15 signature.

WILLIAM L. McGINLEY.
